(57) **CLAIM**

The ornamental design for an electric ukulele, as shown and described.

DESCRIPTION

FIG. 1 is a perspective view of a first embodiment of a present invention electric ukulele;

FIG. 2 is a right elevational view of the first embodiment of the electric ukulele;

FIG. 3 is a left elevational view of the first embodiment of the electric ukulele;

FIG. 4 is a top plan view of the first embodiment of the electric ukulele;

FIG. 5 is a bottom plan view of the first embodiment of the electric ukulele;

FIG. 6 is a back elevational view of the first embodiment of the electric ukulele;

FIG. 7 is a front elevational view of the first embodiment of the electric ukulele;

FIG. 8 is a perspective view of a second embodiment of a present invention electric ukulele;

FIG. 9 is a right elevational view of the second embodiment of the electric ukulele;

FIG. 10 is a left elevational view of the second embodiment of the electric ukulele;

FIG. 11 is a top plan view of the second embodiment of the electric ukulele;

FIG. 12 is a bottom plan view of the second embodiment of the electric ukulele;

FIG. 13 is a back elevational view of the second embodiment of the electric ukulele; and,

FIG. 14 is a front elevational view of the second embodiment of the electric ukulele.

The broken line showing of various components of an electric ukulele in FIGS. 1-7 are for illustrative purposes only and form no part of the claimed invention. Similarly, the broken line showing of various components of an electric ukulele in FIGS. 8-14 are for illustrative purposes only and form no part of the claimed invention.
